UNITED STATES PATENT OFFICE.

JOHN ARTHUR HAYHOE, OF LONDON, ENGLAND.

ILLUMINATED UMBRELLA AND WALKING STICK.

Application filed January 12, 1928, Serial No. 246,212, and in Great Britain January 24, 1927.

This invention relates to umbrellas and walking sticks.

An object of the invention is to combine with umbrellas and walking sticks, means whereby visual warning can be given to drivers of vehicles of the presence of a pedestrian in a dark road. Another object is to provide an umbrella stem or walking stick with light emitting means adapted to be operated by pressure of the ferrule or end of the stick against the ground, which pressure naturally occurs when the stick or umbrella is used as a support for the hand while walking or standing, and is thus practically automatic. Another object is to render the action of the said light emitting means intermittent. Another object is to enable the action of the light emitting means to be suspended and restored at will. Another object is to provide light emitting means as aforesaid in a readily detachable part of the stick or umbrella so that the said part can be used when detached as a torch or flashlight. Further objects and advantages of this invention will be apparent from the following description read in conjunction with the accompanying drawings, which illustrate by way of example two embodiments of the invention.

30 Figure 1 represents in longitudinal section a portion of a stick which may be either a walking stick or the stick of an umbrella.

Figure 2 represents a modification, the stick being shown in elevation with the knob and ferrule shown in section and detached from the stick.

Figure 3 is an elevation partly in section of an inner tube for holding the lamp, batteries, and master switch holder detached from the stick shown in Figure 2.

40 Figure 4 is an elevation of a master switch with its holder in section.

A represents a hollow upper portion of a stick, which as aforesaid may be either a walking stick or the stick of an umbrella. B represents the knob or handle, which may be of any desired shape but is here represented as a rounded knob, and may be of any suitable material. In the example given in 45 Figure 1, the part A is a brass tube on which is firmly secured a collar 19 outside which slides freely a collar 11, which is externally screw threaded over a portion of its length and forms a shoulder 12. A brass collar 13 surrounds the top of the tube A

and is retained in position by a fluting or projecting ring 14 formed in the substance of the tube, the purpose of this collar 14 being to prevent the knob from being entirely lifted off the stick. The knob B which 50 may conveniently be made in two portions 15 and 16 permanently connected together as for example by screw threaded engaging surfaces at 17, has a brass plate 18 secured under its roof by a screw 20, and a spring 21 is also anchored to the said plate 18 by the said screw 20. The lower part of the knob is internally screw threaded to engage the thread 23 on the collar 11 and has an annular abutment 24 to engage the shoulder 70 55 12 on the said collar 11. The other end of the tube A is provided with a screw threaded spigot 25 engaging an internally screw threaded part of the stick 26 which in the case of a tubular metal stick may be an integral part thereof, and in the case of a wooden stick may be a socket secured on a reduced part 27 of the stick as shown in Figures 1 and 2. An electric battery 28 is 60 freely enclosed in the tube A, and is adapted to be connected through a contact piece 30 with a glow lamp 31 secured to the spigot 25. In the walls of the socket 26 are a number of oval or other openings 32, say four, through which light emitted from the glow 65 lamp 31 is visible externally. A corresponding number of pieces 33 of glass, preferably red, are placed inside the openings 32, or a ring or sleeve of transparent material may 70 equivalently form a lining for the socket 90 26. In the position illustrated in Figure 1, the device is in its inoperative position, the electrical circuit being broken between the top of the brass tube A and the underside of the plate 18, and the fixed collar 19 95 prevents depression of the knob B and collar 11. When either by rotating the knob to draw up the collar 11 or rotating the collar 11 to cause it to rise on the knob and leave a clearance between the top of the fixed 100 collar 19 and the inside of the collar 11 the knob can be pressed down until the sliding movement of the collar 11 is stopped by the collar 19, a clearance then existing between the underside of the collar 13 and the 105 part of the knob immediately below it. In this depressed position a circuit is completed from the battery 28 through the contact piece 30, lamp 31, spigot 25, tube A, plate 18, and spring 21, when the light of the lamp 110

becomes visible through the openings. On releasing the knob, the spring 21 lifts the plate 18 clear of the top of the tube A and breaks the circuit, and by repeated pressure of the hand on top of the knob and alternately removing such pressure the light can be exhibited intermittently. The knob being held by the user and the free end of the stick pressed against the ground, or 10 against any other rigid object such as a wall or a tree, the pressure of the hand on the knob causes the knob to slide down on the tube, bringing the plate 18 into contact with the tube A and completing the circuit 15 through the lamp. In walking, the stick will be alternately pressed on the ground and lifted, and at each lifting movement the spring 21 by its expansion lifts the knob and separates the plate 18 from the tube A, 20 breaking the circuit. The exhibition of the light is thus rendered intermittent, whereby rapid exhaustion of the battery is avoided, and also an intermittent light is more likely to attract attention to the position of the 25 user than a continuous light of small power. It is desirable that the circuit should remain broken during daylight or in well lighted streets where the exhibition of a light by a pedestrian would be unnecessary. For this 30 purpose the collar 11 is placed in the position shown so as to prevent the knob B from sliding down the tube under pressure of the hand, so that the plate is kept clear of the tube A. Thus the control of the lamp by 35 the automatically acting means can be suspended and restored at will.

By unscrewing the upper part of the stick from the socket 26 so that the lamp is exposed, and placing the collar 11 in its operative position, the said upper part can be used as an ordinary flashlight or electric torch.

Referring now to Figures 2, 3 and 4, the stick may be of wood, aluminium, or of any 45 other suitable material and of any desired external configuration or ornamentation, but in the example it is assumed to be a slightly tapering smooth tube of ebonite wholly or partially lined with brass and 50 pierced with one or more holes at 32; for instance there may be two circular holes diametrically opposite one another and glazed with ruby glass or other transparent material, a strengthening band 40 of silver 55 or other metal being provided at the level of the holes 32 and correspondingly perforated. Instead of two holes 32 there may be three or four of such holes spaced apart around the circumference of the stick. At 60 the top of the stick a projecting part of the lining 41 is externally screw threaded and slotted at 42, there being preferably two diametrically opposite slots. A brass inner tube 43 (Figure 3) is provided with ribs 65 44 to register in the said slots 42, this tube

having at its lower end an internally screw threaded sleeve 45 insulated from the tube 43 by an outer sleeve 46 of insulating material. An electric lamp 31 is screwed into the sleeve 45 and is in contact with a pin 47 70 passing through an insulating partition 48, the length of the tube 43 being such that when it is in position the lamp 31 is opposite the holes 32. In the tube 43 above the partition 48 are two batteries in series 75 28, 28^a and a master switch 50 resiliently supported in its insulator 51 and carried in a holder 52, this holder having at its upper extremity a flanged or overlapping roof 53 which is adapted to make contact with the 80 top of the tube 43, the switch 50 being insulated from the said holder and normally in contact with the upper terminal of the battery 28. A spring 54 confined in the holder tends to keep the switch 50 out of 85 contact with the inner surface of the roof 53. The knob B is internally screw threaded to engage the lining 41, and contains a pin 55, which when the knob is screwed home presses down the roof 53 of the master 90 switch holder against the resistance of the spring 54 to make contact with the switch 50 and lining 41, the lamp 31 being thereby placed in circuit with the lining 41. At the bottom of the stick is a brass tube 56 in 95 electrical connection with the lining 41, concentric with which tube is positioned a switch member 57 suitably insulated from the tube and electrically connected with the sleeve 45. A spring 58 confined in the detachable brass ferrule normally keeps the 100 switch member 57 from contact with the bottom of the said ferrule, which ferrule however is capable of a sliding movement of small extent in relation to the tube 56, to 105 which it is attached by a set screw 61 working in a slot in the said tube 56, so that when the extremity of the ferrule (which may be shod with iron) is pressed against the ground, the electrical circuit is completed from the member 57 through the ferrule 60, tube 56, lining 41, lamp 31, and sleeve 45. This circuit can be broken by loosening or screwing back the knob B so that the spring 54 disconnects the parts 50 110 and 53.

Where only one switch is employed, it may be located in the ferrule, the circuit being closed by pressure exerted longitudinally of the stick from the handle towards the 120 ground; or where both an automatic switch and a master switch are employed, the former may be located either in the handle or the ferrule.

Although I have herein described examples of means by which the objects of this invention can be accomplished, it is obvious that the form and construction of the devices described can be varied while still accomplishing such objects, and I do not de- 125 130

sire to limit my invention to the exact details described, but that it shall be understood to cover all such variations as are fairly included within the scope of the following claims.

What I claim and desire to secure by Letters Patent of the United States is:—

1. In a walking stick or umbrella, a stem comprising a detachable hollow portion, an 10 electric battery contained therein, a lamp carried at one end of said portion, a handle carried at the other end thereof, said handle being slideable on said stem to complete an electrical circuit through said battery and 15 lamp, and means for automatically revers-

ing said sliding movement to break said circuit.

2. In a walking stick or umbrella, a stem provided with a fast collar, an externally screw threaded outer collar slideable on said 20 fast collar, light emitting means carried by said stem, a handle slideable on said stem to operate said light emitting means, said handle being internally screw threaded to engage said slideable collar, said slideable collar being longitudinally adjustable to restrain the sliding movement of said handle, whereby the operation of said light emitting means can be suspended when so desired.

JOHN ARTHUR HAYHOE.
